By Attorney

UNITED STATES PATENT OFFICE.

HARRY STREET SLADE, OF MCKEESPORT, PENNSYLVANIA.

ATTACHMENT FOR TOOTH-PASTE TUBES.

1,336,966.

Specification of Letters Patent.

Patented Aug. 9, 1921.

Application filed January 29, 1920. Serial No. 355,009.

To all whom it may concern:

Be it known that I, HARRY S. SLADE, a subject of the King of England, residing at McKeesport, in the county of Allegheny and 5 State of Pennsylvania, have invented certain new and useful Improvements in Attachments for Tooth-Paste Tubes; and I do hereby declare the following to be a full, clear, and exact description of the invention, 10 such as will enable others skilled in the art to which it appertains to make and use the same, reference being had to the accompanying drawings and to the letters and figures of reference marked thereon, which form a part 15 of this specification.

This invention relates to new and useful improvements in attachments for tooth paste or shaving cream tubes, the object of the invention being to provide a simple device 20 which is thoroughly practical for extruding paste from paste holders, such as the ordinary collapsible tin tubes containing tooth paste or shaving cream.

The drawings clearly show by preferred 25 form of the invention, and in which:

Figure 1 is a view in side elevation of my device.

Fig. 2 is an end view looking at the left hand end of Fig. 1.

Fig. 3 is a top plan view.

Fig. 4 is a detail view of the hinge end of the device and,

Fig. 5 is a fragmentary view in perspective of the device.

Referring now in detail to the drawings:

1 designates a plate or bar which is bent at one end, as shown at 2. 3 designates a second plate or bar provided with a bent end 4 which is hinged, as shown at 5, to the 40 end 2. The plate 3 is bent at its opposite end, as shown at 6.

7 is an end plate of spring material suitably secured to the plate 1 and having a lateral transversely curved terminal 8, 8, said 45 end plate and terminal being slotted at 9.

Rotatably journaled in the bent portion 2, and in the end plate 7, is a roller 10 which is milled on its periphery, as shown in the drawing. A second roller 11 is rotatably 50 journaled in the ends 4 and 6 of the plate 3. Said rollers are provided at one end, exteriorly of the end plate 7, with intermeshing

gears 12, 12. One of the rollers, as for instance the roller 10, is provided with suitable means for rotating the same, and thus 55 the second roller. In this instance, such means comprises a hand twirler 13 secured on the end of the shaft of the roller 10.

In operation, it will be seen that by rotating the twirler 13, the roller 10 will be rotated, and through the medium of the gears 12, 12 the other roller 11 will simultaneously be rotated, said rollers rotating in reverse directions.

The device may be quickly placed on the 65 end of a tube by swinging the side plate 3 on its hinge 5 away from the rollers 10, disposing the tube end between the rollers 10 and 11, and then swinging said side plate 3 so as to bring the rollers 10 and 11 in juxtaposition, the bent terminal 6 of the side plate 3, contacting with the curved terminal 8 and flexing said end plate 7 outward, said plate thereupon springing back after the terminal 6 passes by the curved terminal 8, thus causing the terminal 8 to bear against the outer surface of the plate 3, frictionally holding the same against accidental outward movement. A pin 3', carried by the terminal 6, 70 rides in the slot 9, and limits inward move- 75 ment of the side plate 3.

The spring fingers 8, 8 yieldingly hold the plate 3 in closed position against opening movement on the hinge 5. By manipulating the hand twirler 13 the material in the 85 tube may be fed therefrom as desired, the tube being forced downward by the rollers 10 and 11 as the material is extruded from the open end of the tube.

What I claim to be new is:

A device for feeding material from a tube comprising parallel bars having perpendicular offsets at their ends, the juxtaposed offsets at one end being hinged together, a latch holding the bars separably united at 95 their ends opposite the hinge, parallel milled rollers journaled in the offsets, a knurled head connected with one of the rollers at the hinged end, and intermeshed gears carried by the rollers at the latch end adapted to be 100 separated when the bars are unlatched.

In testimony whereof I hereunto affix my signature.

HARRY STREET SLADE.
